United States Patent Office

Des. 223,865
Patented June 13, 1972

223,865

CALCULATOR

Shiro Anzai and Minoru Murata, Kanagawa-ken, Tatsuo Nishikawa, Tokyo, and Takamitsu Hanakata, Kanagawa-ken, Japan, assignors to Canon Kabushiki Kaisha, Tokyo, Japan

Filed Oct. 12, 1970, Ser. No. 25,431

Claims priority, application Japan Apr. 13, 1970

Term of patent 14 years

Int. Cl. D18—01

U.S. Cl. D64—11

Fig. 1.

Fig. 2.

Fig. 3.

FIG. 4.

FIG. 6.

FIG. 7.

FIG. 5.

FIG. 1 is a front perspective view of a calculator embodying our new design;

FIG. 2 is a rear perspective view of the calculator of FIG. 1;

FIG. 3 is a side elevational view of the calculator of FIGS. 1 and 2;

FIG. 4 is a top plan view of our calculator;

FIG. 5 is a view similar to FIG. 3 but taken from the opposite side of the calculator;

FIG. 6 is an end elevational view; and

FIG. 7 is a view similar to FIG. 6 but taken from the opposite end thereof.

We claim:

The ornamental design for a calculator, as shown.
